UNITED STATES PATENT OFFICE.

HARRY CLARENCE PHILLIPS, OF GLOUCESTER, ENGLAND.

ROTARY PRIME MOVER, MOTOR, COMPRESSOR, PUMP, AND THE LIKE.

Application filed August 13, 1923. Serial No. 657,166.

To all whom it may concern:

Be it known that I, HARRY CLARENCE PHILLIPS, a subject of the King of Great Britain, residing at Gloucester, England, have invented certain new and useful Improvements in and Relating to Rotary Prime Movers, Motors, Compressors, Pumps, and the like, of which the following is a specification.

10 This invention relates to rotary prime movers, motors, compressors, pumps, and the like, and has for its object to provide simple means by which power may be utilized or distributed to perform work in a most 15 efficient manner.

The machine is of the type consisting of a horizontal cylinder within which is a rotor mounted eccentrically to the cylinder bore, the rotor being formed peripherally with a 20 number of channels in which work radially slidable blades moving outward under centrifugal force so as to press against the wall of the cylinder when the rotor revolves.

Referring to the accompanying drawings 25 illustrating a preferred construction,

Fig. 1 is a cross section of the rotor.

Fig. 2 is an axial section.

Figs. 3, 4 and 5 are modifications in the form of the blades.

30 In carrying the invention into effect with reference to Figs. 1 and 2, upon a shaft 1 is mounted a rotor 2 of cylindrical form having axially disposed channels 3 open at the periphery, these channels extending from side to side thereof. Said rotor is eccentrically mounted in a cylinder 4 which is provided on opposite sides thereof with an inlet 5 and an outlet 6. Radially slidable within the channels 3 are blades 7 which are laterally tapered outwardly, and inwardly truncated so as to present concave faces 7^a to the axis of the rotor 2. The sides of the blades 7 continuing inwardly from their tapering sides may assume a slight convexity 40 7^b leading up to the said concave faces. As shown, the blades 7 are solid, but it is to be understood that they may be chambered as desired.

So constructed, there is, at all times, a simple line-contact between each wall of each of the channels 3 and the corresponding wall or face of the blade 7 which slides therein, the line-contacts being substantially parallel with the axis of the rotor. This reduces 55 friction to the minimum. It also provides a constantly varying surface of contact be-

tween the faces of each blade and the corresponding walls of the respective channels and permits a rocking action of each blade relatively to its respective channel and to the axis of the rotor, so that all blades instantly accurately accommodate themselves to their channels at every point in the travel of the rotor. This construction and line contact permitting rocking and sliding contact of the blades, also assures continuous contact between the outer face of each blade and the interior wall of the cylinder.

The rotor 2 is provided interiorly with a series of ducts 8 in three different planes as shown in Fig. 2 for example. The ducts 8 provide intercommunication between the channels 3 at the back of the blades 7, and a common pressure is thus maintained on the inside of said blades. In order to maintain a requisite pressure at the inside of the blades, there is arranged in the rotor 2 between the channels, a series of non-return ball valves 9 or other suitable valves, which control the admission of fluid to the middle series of ducts, although the valves may be fitted to the outer ducts if desired. The valve seatings 10 are screwed or connected radially in the rotor 2, one or more being situated between neighboring blades 7 and controlling access to the said ducts by way of openings 11 or the like formed within the rotor 2. The said valve seatings may be formed with outer flanges 12 abutting against the bottom of recesses in the rotor 2 and thereby derive position and lie within the confines of the latter.

With this construction, should the fluid at the inside of the rotor fall below a certain pressure, the outside fluid forcing open the valves 9 passes to the interior of the rotor and presses the blades 7 against the walls of the cylinder 4.

When the machine is to be used as a prime mover, motor, or the like, the shaft 1 may be disposed as shown above the centre of the cylinder 4, so that the blades 7 which are at the lower half of the rotor 2 when the machine is at rest, or rotating at relatively slow speed, will tend to move out of the channels 105 against the bore of the cylinder 4 and be positioned for action by the fluid pressure.

When the machine is to be used as a transmitter of power, such as a pump, compressor, or the like, the shaft 1 may be disposed below the centre of the cylinder 4, whereupon the blades 7 which are at the upper

half of the rotor 2 will tend to sink into their channels 3 when the machine is at rest and when same is being rotated at a relatively slow speed. By this means, the rotor 2 with its blades 7 may be rotated without imparting motion to the fluid medium or tending to impart only a relatively small motion thereto. Thus the prime mover which may be utilized to drive the machine as a power transmitter may be easily started up and the necessity for clutch devices or the like may be obviated. When the speed of the machine is increased, however, centrifugal force will cause the blades 7 to move outwards until they bear against the bore of the cylinder 4, thus obtaining the maximum inlet and discharge of the fluid medium. By this action, the movement imparted to the said medium may be caused to commence gradually and without shock.

Alternatively, the rotor may be devoid of non-return valves.

In a modified form shown in Fig. 3, flexible plates 13 or the like are attached to the blades 7, said plates being disposed at the sides thereof and adapted to press closely against the inside faces of the channels 3 by any pressure which may be set up in the interior of the rotor.

In the modified form shown in Fig. 4, the flexible plates 13^a are formed integrally with the blades 7 and are adapted to engage the inside faces of the channels 3 as aforesaid.

In the modified form shown in Fig. 5, the inner part 7^b of the blades 7 is shown as convexed.

The eccentricity of the rotor shaft 1 in relation to the cylinder 4 may be such that the interior space of the rotor 2 may remain at a constant capacity in all positions which the said rotor may assume whilst rotating.

The channels and blades may be provided with hard metal liners if required.

What I do claim as my invention, and desire to secure by Letters Patent, is:—

1. In a rotary prime mover, motor, compressor, pump, or the like, the combination of a cylinder, a rotor eccentrically mounted therein, channels open at the periphery of the rotor, outwardly tapered blades freely movable in the channels, said blades having their taper sides leading to a broad outer end adapted to engage the bore of the cylinder, and with convex rear parts permitting engagement with the walls of the channels, and inlet and outlet ports in the cylinder at the sides of the rotor.

2. In a rotary prime mover, motor, compressor, pump, or the like, the combination of a cylinder, a rotor eccentrically mounted therein, channels in the rotor open at the periphery, radial blades movable in the channels, said blades tapering to a broad end engaging with the cylinder, ducts formed interiorly of the rotor, said ducts being open

to the inner part of the blades, and holding fluid under pressure for maintaining the blades against the bore of the cylinder.

3. In a rotary prime mover, motor, compressor, pump, or the like, the combination of a cylinder, a rotor eccentrically mounted therein, channels open at the periphery of the rotor, outwardly tapered blades freely movable in the channels, said blades having their taper sides leading to a broad outer end adapted to engage the bore of the cylinder, ducts formed in the rotor, said ducts affording intercommunication to the inner part of the blades, radial valves disposed in the rotor adapted to admit ingress of motive fluid to the ducts, and inlet and outlet openings in the cylinder at opposite sides of the rotor.

4. In a rotary prime mover, motor, compressor, pump, or the like, the combination of a cylinder, a rotor eccentrically mounted therein, channels open at the periphery of the rotor, outwardly tapered blades freely movable in the channels, said blades having their taper sides leading to a broad outer end adapted to engage the bore of the cylinder, intercommunicating ducts in the rotor at the inner part of the blades, ball or other valves disposed in the rotor between the blades, valve seating members for the ball or other valves, connected within the rotor, said ball or other valves being adapted to admit ingress of fluid to the ducts and to serve as non-return valves for preventing egress of fluid from the interior of the rotor.

5. In a rotary prime mover, motor, compressor, pump, or the like, the combination of a cylinder, a rotor eccentrically mounted therein, channels open at the periphery of the rotor, outwardly tapered blades freely movable in the channels, said blades having their taper sides leading to a broad outer end adapted to engage the bore of the cylinder, flexible plates or the like members integrally formed with or attached to the sides of the blades and adapted to press against the inside faces of the channels, radial valves disposed in the rotor between the blades, and inlet and outlet openings in the cylinder at opposite sides of the rotor.

6. In a rotary prime mover, motor, compressor, pump, or the like, the combination of a cylinder, a rotor eccentrically mounted therein, channels open at the periphery of the rotor, outwardly tapered blades freely movable in the channels, said blades having their taper sides leading to a broad outer end adapted to engage the bore of the cylinder, with convex rear portions permitting engagement with the walls of the channels, radial valves disposed in the rotor, interior ducts within the rotor controlled by the valves for admitting ingress of fluid or preventing non-return of fluid from said

ducts, and inlet and outlet ports at opposite sides of the rotor.

7. In a rotary prime mover, motor, compressor, pump, or the like, the combination of a cylinder, a rotor eccentrically mounted therein, and provided with radially disposed channels, and blades slidably and rockably mounted in said channels and having variable line-contact with said channels. 15
- 5 8. In a rotary prime mover, motor, compressor, pump, or the like, the combination

of a cylinder, a rotor eccentrically mounted therein and provided with radially disposed channels, and blades slidably and rockably mounted in said channels and having variable line-contact with said channels.

In testimony whereof, I have signed my name to this specification at Gloucester, England, this 16th day of July, 1923.

HARRY CLARENCE PHILLIPS.
